UNITED STATES PATENT OFFICE.

WALTER A. BARROWS, OF CHICAGO, ILLINOIS.

DESIGN FOR A GAS-LAMP.

SPECIFICATION forming part of Design No. 30,447, dated March 28, 1899.

Application filed February 27, 1899. Serial No. 707,111. Term of patent 7 years.

To all whom it may concern:

Be it known that I, WALTER A. BARROWS, a citizen of the United States, residing at Chicago, in the county of Cook and State of Illinois, have invented and produced a new and useful Design for Gas-Lamps, of which the following is a specification.

The accompanying drawings represent my design for a gas-lamp, in which—

10 Figure 1 is a side elevation of the lamp; Fig. 2, a plan view thereof; and Figs. 3 and 4, front and rear elevations, respectively, thereof.

15 The lamp, as shown, consists of a cylindrical burner-chamber A, having a lens a , side lights a' , and a chimney a^2 . The cylindrical water-chamber B is of the same diameter as the burner-chamber and adjoins the same at the rear thereof. This water-chamber has a valve-stem b thereon, with a cap b'

on the top for the admission of water, and has a rounded end portion b^2 .

The carbid-chamber C is a cylindrical cup whose axis is at right angles to the axes of the other chambers and has an outlet-pipe c , 25 leading up its side into the burner-chamber, and also has a clamping-lug c' .

The whole arrangement and relation of parts presents an attractive appearance and gives a pleasing effect to the eye of the observer and one that is harmonious and at once distinctive.

I claim—

The design for a gas-lamp substantially as herein shown and described.

WALTER A. BARROWS.
